OIL WELL PUMP

Ralph R. Renouf, Los Angeles, and Frank E. Mason, South Gate, Calif., assignors to Emsco Derrick & Equipment Company, Los Angeles, Calif., a corporation of California

Application March 23, 1945, Serial No. 584,430

14 Claims. (Cl. 103—221)

1

Our invention relates to an improvement in reciprocating pumps employed in oil wells to pump oil therefrom, and relates in particular to an improved plunger pump and tubing arrangement wherein the diameter of the pump plunger is considerably larger than the diameter of the opening through the tubing.

It is necessary to periodically remove oil well pumps from the wells in which they operate in order to repair or replace worn parts. Where the pump employed is larger in diameter than the tubing by which it is supported, it is necessary in order to remove the pump from the well to pull the string of tubing, having the pump attached to the lower end thereof, to the top of the well. In doing this a number of difficulties have been encountered. At the end of a pumping period the tubing is full of oil, and unless this oil is drained from the tubing before it is removed from the well, there will be what is known as a wet job, involving the spilling of large quantities of oil in the derrick. In order to avoid this condition, a number of different types of bleeders have been employed, which have not been found to be entirely satisfactory. It is an object of the present invention to provide a simple pump structure employing a large diameter pump on small diameter tubing having simple and effective means whereby the oil may be drained from the tubing and from the pump before or during the lifting of the tubing, so that as the tubing is removed from the well it will be in a condition known as dry, and spillage of oil upon the derrick floor will be avoided.

It is an object of the invention to provide a pumping structure having a tubular extension projecting upwardly from the working barrel of the pump, this tubular extension being so formed as to provide a space into which the pump plunger may be raised so as to be out of the working barrel and so as to provide a passage or passages through which the oil may flow downward around the exterior of the raised pump plunger. The invention provides simple means for opening the lower end of the pump so that oil may flow therethrough, and for holding the plunger in its position raised within the tubular extension, so that oil may freely drain from the tubing and the pump proper during the lifting of the tubing and the pump in the well.

It is an object of the invention to provide a pump structure of the character set forth in the preceding paragraph having a simple form of hanger for supporting the plunger in a raised position above the working barrel and also having

2

means for lifting the standing valve of the pump from its seat.

A further object of the invention is to provide simple attachments which may be applied to many existing pumps so that they may be used with tubing of internal diameter smaller than the external diameter of the pump plunger.

Further objects and advantages of the invention will appear in the following part of the specification which describes a preferred form of the invention.

Referring to the drawing which is for illustrative purposes only,

Fig. 1 is a sectional view of the pump structure with the parts thereof disposed for normal pumping operation.

Fig. 2 is a sectional view showing the pump structure raised from the working barrel and the standing valve lifted from its seat.

Fig. 3 is an enlarged fragmentary sectional view taken as indicated by the line 3—3 of Fig. 2.

The pump structure includes a pump body 10 having a working barrel 11 and a standing valve 12 supported by a seat 13. Extending upward from the barrel 11 there is a tubular extension 14 of larger internal diameter than the barrel 11 and of greater length than the barrel 11. A plunger 15 is operative within the barrel 11, this plunger 15 having the customary working valve 16. A short rod 17 extends upward to a body 18 which forms a first locking part for cooperating with other parts to hold the plunger 15 in the raised position in which it is shown in Fig. 2. This body 18 has projecting lugs 19. A rod 20, connected to the upper part of the body 18, extends upwardly therefrom through a hanger member 21 to an attachment device 22 for connecting the rod 20 to the lower end of a string of sucker rods 23, which is employed to transmit movement to the plunger 15. For example, by reciprocation of the string of sucker rods 23, the plunger 15 may be caused to reciprocate within the working barrel 11 and perform the normal pumping operation, or by lifting on the sucker rods 23, the plunger 15 may be raised into the tubular extension 14.

The hanger member 21 comprises a sleeve 24 which is threaded onto the upper end of the tubular extension 14 and has internal threads 25 at its upper end to receive the external threads 26 of a tubular hanger body 27 which is internally threaded at 28 to receive the lower end 29 of a string of tubing having an internal diameter less than the external diameter of the plunger 15, so that it is not possible to pull the plunger 15

through the tubing 30. The hanger body 27 has an internal cylindric wall or skirt 31 having diametrically opposed slots 32 extending upward from the lower end thereof, the upper portions 33 of these slots 32 bending laterally and leading into pockets or depressions 34 to receive the lugs or projections 19 of the body 18. The projections 19 provide downwardly faced shoulders to engage the upwardly faced shoulders 35 comprising the bottoms of the depressions 34, whereby the pump plunger 15 may be supported and locked in the raised position in which it is shown in Fig. 2. The lower end of the wall 31 of the hanger body 27 is formed so as to provide sloping faces 36 to guide the projections 19 into the slots 32.

In the pump structure we provide standing valve lifting means 37, whereby the standing valve 12 may be picked up from the position in which it is shown in Fig. 1 and raised with the plunger 15 into the position in which the standing valve 12 is shown in Fig. 2. There are a number of standing valve pullers or lifters now available in the oil pumping industry which may be used between the plunger 15 and the standing valve 12 to lift the standing valve 12. Preferred however in the practice of the invention is the standing valve puller shown in the application of Ralph R. Renouf, Serial No. 523,243, filed February 21, 1944, for Standing valve puller, which provides an upwardly projecting bar 38 for the standing valve 12, having a T head 39 adapted to enter a hollow pick-up element 40 which is connected to the lower end of the plunger 15, when the plunger is lowered from the position in which it is shown in Fig. 1, this T head 39 being engaged as shown in Fig. 2, so that when the plunger 15 is lifted, the standing valve 12 will be pulled from the seat 13 and lifted with the plunger 15 into the tubular extension 14.

The attachment 22 is a device for connecting and disconnecting the sucker rods to or from the plunger 15 while the pump structure is in the well. The one we have shown for this purpose is known to the trade as "The O'Bannon On and Off Device," and consists of a lower body 41 which is screwed onto the upper end of the rod 20 and an upper body which is screwed onto the lower end of the string of sucker rods 23. The lower body 41 has an upwardly projecting threaded stem 43, and the upper body 42 comprises an internally threaded sleeve to receive the threaded stem 43. The threads of the stem 43 and of the upper body 42 are ordinarily right hand so that by application of left hand torque to the upper end of the string of sucker rods 23, the upper part 42 may be unscrewed from the lower part 41, permitting the string of sucker rods to be lifted independently through the tubing 29. The tubular extension 14 consists of a length of standard pipe which may be readily connected to the upper end of many standard pumps. The hanger member 21 is so formed that it may be readily connected to the upper end of the tubular extension 14 so as to serve as a means for connecting the lower end of the string of tubing 29 to the tubular extension 14 and therefore to the pump proper.

The operation of the pump structure when it is desired to pull the pump from the well, is as follows. The plunger 15 is first lowered from the position in which it is shown in Fig. 1 so as to cause the pick-up element 40 to engage the T head 39 associated with the standing valve 12. The sucker rod string is then pulled up so as to lift the body 18 into such position that the projections 19

thereof will engage the hanger body 27. The sloping walls 36 guide the projections 19 into the slots 32 and when the upper ends of the slots 32 are reached, a clockwise rotation applied to the string of sucker rods 23 will bring the projections 19 into alignment with the depressions 34, so that when the string of sucker rods is now lowered, the projections 19 will pass downward into the depressions or recesses 34 and rest against the bottoms 35 thereof, supporting or hanging the pump plunger 15 and the standing valve 12 in raised position within the tubular extension 14. When the plunger 15 and the standing valve 12 are in the positions thereof shown in Fig. 2, oil may flow freely downward from the interior of the tubing 29 around the exterior of the plunger 15 and the exterior of the standing valve, and then through the barrel 11 and the opening provided by the standing valve seat 13 to the exterior.

After the plunger 15 and the standing valve 12 are thus hung in raised position as shown in Fig. 2, the string of sucker rods 23 may be disconnected from the pump plunger by unscrewing the attachment 22, enabling the pulling of the sucker rod string prior to the pulling of the tubing and pump from the well. Now, as the tubing 29 is lifted from the well, oil may continue to drain therefrom, so that as the sections of tubing are unscrewed at the top of the well, they will be comparatively dry.

We claim as our invention:

1. In a pump structure of the character described, adapted to be connected to the lower end of a string of tubing in a well, the combination of: a working barrel; a tubular extension projecting upward from said barrel; a standing valve at the lower end of said barrel; a plunger operative in said barrel; standing valve lifting means operative between said plunger and said standing valve whereby said standing valve may be lifted; sucker rod means for operating said plunger in said working barrel and for lifting said plunger into said tubular extension, there being a space provided by said tubular extension through which liquid may flow down past said plunger when it is raised into said tubular extension; and means for holding said plunger raised into said extension during the time the tubing and the pump are being raised from the well.

2. In a pump structure of the character described, adapted to be connected to the lower end of a string of tubing in a well, the combination of: a working barrel; a tubular extension projecting upward from said barrel; a standing valve at the lower end of said barrel; a plunger operative in said barrel; standing valve lifting means operative between said plunger and said standing valve whereby said standing valve may be lifted; sucker rod means connected with said plunger and disconnectable therefrom so that it may be removed from said string of tubing prior to the time the tubing and pump are being raised from the well, said sucker rod means being adapted to operate said plunger in said working barrel and to lift said plunger into said tubular extension, there being a space provided by said tubular extension through which liquid may flow down past said plunger when it is raised into said tubular extension; and means for holding said plunger raised into said extension.

3. In a pump structure of the character described, adapted to be connected to the lower end of a string of tubing in a well, the combination of: a working barrel; a tubular extension project-

ing upward from said barrel; a standing valve at the lower end of said barrel; a plunger operative in said barrel; standing valve lifting means operative between said plunger and said standing valve whereby said standing valve may be lifted; sucker rod means removably connected with said plunger, said means being adapted to operate said plunger in said working barrel and to lift said plunger into said tubular extension, there being a space provided by said tubular extension through which liquid may flow down past said plunger when it is raised into said tubular extension; and hanger means comprising cooperating parts connected to said plunger and to said extension for holding said plunger raised into said extension.

4. In a pump structure of the character described, adapted to be connected to the lower end of a string of tubing in a well, the combination of: a working barrel; a tubular extension projecting upward from said barrel; a standing valve at the lower end of said barrel; a plunger operative in said barrel; standing valve lifting means operative between said plunger and said standing valve whereby said standing valve may be lifted; sucker rod means for operating said plunger in said working barrel and for lifting said plunger into said tubular extension, there being a space provided by said tubular extension through which liquid may flow down past said plunger when it is raised into said tubular extension; a first locking member connected to the upper end of said plunger, said member having a downwardly faced shoulder; and a second locking member fixed in a position elevated from the lower end of said tubular extension, said second locking member having an upwardly faced shoulder for engagement by said downwardly faced shoulder of said first locking member, whereby said plunger may be held in a raised position in said tubular extension.

5. In a pump structure of the character described, adapted to be connected to the lower end of a string of tubing in a well, the combination of: a working barrel; a tubular extension projecting upward from said barrel; a standing valve at the lower end of said barrel; a plunger operative in said barrel; standing valve lifting means operative between said plunger and said standing valve whereby said standing valve may be lifted; sucker rod means for operating said plunger in said working barrel and for lifting said plunger into said tubular extension, there being a space provided by said tubular extension through which liquid may flow down past said plunger when it is raised into said tubular extension, the lower portion of the sucker rod means being disconnectable from the plunger, whereby said sucker rod means may be lifted independently from said tubing; a first locking member connected to the upper end of said plunger, said member having a downwardly faced shoulder; and a second locking member fixed in a position elevated from the lower end of said tubular extension, said second locking member having an upwardly faced shoulder for engagement by said downwardly faced shoulder of said first locking member, whereby said plunger may be held in a raised position in said tubular extension.

6. In a pump structure of the character described, adapted to be connected to the lower end of a string of tubing in a well, the combination of: a working barrel; a tubular extension projecting upward from said barrel; a standing valve

at the lower end of said barrel; a plunger operating in said barrel; standing valve lifting means operative between said plunger and said standing valve whereby said standing valve may be lifted; sucker rod means for operating said plunger in said working barrel and for lifting said plunger into said tubular extension, there being a space provided by said tubular extension through which liquid may flow down past said plunger when it is raised into said tubular extension; a locking body connected to the upper portion of said plunger, said body having a laterally projecting shoulder member; a tubular locking part at the upper end of said tubular extension, said locking part having an upwardly faced shoulder member to be engaged by said shoulder member of said body whereby said plunger may be supported in a position raised into said tubular extension; and disconnectable means for connecting the lower end of said sucker rod means to said locking body whereby movement of said sucker rod means will be imparted to said plunger and the parts connected thereto.

7. In a pump structure of the character described, adapted to be connected to the lower end of a string of tubing in a well, the combination of: a working barrel; a tubular extension projecting upward from said barrel; a standing valve at the lower end of said barrel; a plunger operative in said barrel; standing valve lifting means operative between said plunger and said standing valve whereby said standing valve may be lifted; sucker rod means for operating said plunger in said working barrel and for lifting said plunger into said tubular extension, there being a space provided by said tubular extension through which liquid may flow down past said plunger when it is raised into said tubular extension; a locking body connected to the upper portion of said plunger, said body having a laterally projecting shoulder member; a sleeve threaded to the upper end of said tubular extension; a tubular hanger body threaded to the upper part of said sleeve, said hanger body having an arcuate wall formed so as to define an upwardly faced depression and a slot for leading said shoulder member of said locking body into said depression whereby said plunger may be supported in a position raised into said tubular extension; and disconnectable means for connecting the lower end of said sucker rod means to said locking body whereby movement of said sucker rod means will be imparted to said plunger and the parts connected thereto.

8. In a pump structure for use in a well, the combination of: a working barrel; a tubular extension projecting upward from said barrel; a standing valve at the lower end of said barrel; a plunger operative in said barrel; a string of tubing extending from said tubular extension to the top of the well, said tubing being of internal diameter smaller than the external diameter of said plunger; standing valve lifting means operative between said plunger and said standing valve whereby said standing valve may be lifted; sucker rod means for operating said plunger in said working barrel and for lifting said plunger into said tubular extension, there being a space provided by said tubular extension through which liquid may flow down past said plunger when it is raised into said tubular extension; and means for holding said plunger raised into said extension, said sucker rod means being detachable from said plunger whereby it may be removed

from said string of tubing prior to the time the tubing and the pump are being raised from the well.

9. In a pump structure for use in a well, the combination of: a working barrel; a tubular extension projecting upward from said barrel; a standing valve at the lower end of said barrel; a plunger operative in said barrel; a string of tubing extending from said tubular extension to the top of the well, said tubing being of internal 10 diameter smaller than the external diameter of said plunger; standing valve lifting means operative between said plunger and said standing valve whereby said standing valve may be lifted; sucker rod means for operating said plunger in 15 said working barrel and for lifting said plunger into said tubular extension, there being a space provided by said tubular extension through which liquid may flow down past said plunger when it is raised into said tubular extension; a locking 20 body connected to the upper portion of said body having a laterally projecting shoulder member; a sleeve threaded to the upper end of said tubular extension; a tubular hanger body threaded to the upper part of said sleeve, 25 said hanger body having an arcuate wall formed so as to define an upwardly faced depression and a slot for leading said shoulder member of said locking body into said depression whereby said plunger may be supported in a position raised 30 into said tubular extension; and disconnectable means for connecting the lower end of said sucker rod means to said locking body whereby movement of said sucker rod means will be imparted to said plunger and the parts connected thereto. 35

10. Attachment for a pump structure of the character described having a working barrel and plunger of larger diameter than the tubing by which it is supported in the well, a tubular extension extending upward from the working barrel, a standing valve, and means for opening the standing valve for draining oil from the lower end of the working barrel, the combination of: a locking body for connection to the upper portion of said plunger, said body having a laterally projecting shoulder member; a tubular locking part for connection to the upper end of said tubular extension, said locking part having an upwardly faced shoulder member to be engaged by said shoulder member of said body whereby said plunger may be supported in a position raised into said tubular extension; and disconnectable means for connecting the lower end of said sucker rod means to said locking body whereby movement of said sucker rod means will be imparted to said plunger and the parts connected thereto. 45

11. Attachment for a pump structure of the character described having a working barrel and plunger of larger diameter than the tubing by 60 which it is supported in the well, a tubular extension extending upward from the working barrel, a standing valve, and means for opening the standing valve for draining oil from the lower end of the working barrel, the combination of: a locking body for connection to the upper portion of said plunger, said body having a laterally 65 projecting shoulder member; a sleeve threaded to

the upper end of said tubular extension; a tubular hanger body threaded to the upper part of said sleeve, said hanger body having an arcuate wall formed so as to define an upwardly faced depression and a slot for leading said shoulder member of said locking body into said depression whereby said plunger may be supported in a position raised into said tubular extension; and disconnectable means for connecting the lower end of said sucker rod means to said locking body whereby movement of said sucker rod means will be imparted to said plunger and the parts connected thereto. 8

12. In a pump structure adapted to be connected to a string of tubing in a well and having a working barrel, a plunger operable therein, a tubular extension projecting from said barrel, and a standing valve at one end of said barrel: means adapted to connect the standing valve and the plunger for lifting said valve; means for operating the plunger in the working barrel, said means being adapted to move said plunger into the tubular extension, there being space provided through which liquid may flow past the plunger when it is moved into said tubular extension; and means for holding said plunger in said extension during the time the tubing and the pump are being removed from the well.

13. In a pump structure adapted to be connected to a string of tubing in a well and having a working barrel, a plunger operable therein, a tubular extension projecting from said barrel, and a standing valve supported by a seat adjacent one end of said barrel: means adapted to connect the standing valve and the plunger for removing said valve from said seat; means for operating the plunger in the working barrel, said means being adapted to move said plunger into the tubular extension, there being space provided through which liquid may flow past said plunger when it is disposed in said tubular extension; and means for holding said plunger in said extension. 40

14. In a pump structure adapted to be connected to a string of tubing in a well and having a working barrel, a plunger operable therein, a tubular extension projecting from said barrel, and a standing valve at the lower end of said barrel: means adapted to connect the standing valve to the plunger for lifting said valve; means for operating the plunger in said working barrel, said means being adapted to lift the plunger into the tubular extension, there being a space provided through which liquid may flow past said plunger when it is raised into said tubular extension; and means for holding said plunger in said raised position during the time the tubing and the pump are being removed from the well. 50
